[57] **CLAIM**

The ornamental design for a toy trolley having a dinosaur configuration, as shown and described.

DESCRIPTION

FIG. 1 is a front-right-top perspective view of a toy trolley having a dinosaur configuration, showing my new design;

FIG. 2 is a front elevational view thereof;

FIG. 3 is a rear elevational view thereof;

FIG. 4 is a right side elevational view thereof, the opposite side being a mirror image;

FIG. 5 is a top plan view thereof;

FIG. 6 is a bottom plan view thereof; and,

FIG. 7 is a side elevational view in which the head of the dinosaur of the toy trolley is in another position.

FIG.1

FIG. 2

FIG. 3

FIG. 4

FIG. 5

FIG. 6

FIG.7
